PLATING RACK FOR HEAVY WORK PIECES

Verdun R. McGibbon, Sadsburyville, Albert Grant Taylor, Parkesburg, and George L. Bernard and Donald L. Freyberger, Coatesville, Pa., assignors to Lukens Steel Company, Coatesville, Pa., a corporation of Pennsylvania

Application May 24, 1955, Serial No. 510,696

9 Claims. (Cl. 204—297)

This invention relates generally to electroplating apparatus, and more particularly to racks for holding the articles to be plated during the plating operation. In the electroplating of metal articles such as heavy plates, it is necessary that the plates be properly supported on the racks and readily accessible for attachment thereto and removal therefrom without undue labor or loss of time.

An object of the present invention, therefore, is to provide a plating rack for heavy work pieces, such as bars, plates and billets, which will support said metal work pieces in position for electroplating, such as nickel plating, and to provide a structure for readily loading and unloading the article to be plated from its rack.

Another object is to provide a plating rack having means for making good electrical contact between the work piece and the rack whereby to avoid variable and uncertain current densities and consequent uncertain quality control of the coating.

Various additional objects and features of the invention will become apparent from the following detailed description of one illustrative embodiment thereof, reference being had to the accompanying drawings, in which:

Figure 1 is a side elevational view of the plating rack and the work supported thereon, with the work beam support therefor shown in section;

Figure 2 is a side elevational view of the rack shown in Figure 1, the beam support being shown in section, and the work in dotted lines;

Figure 3 is a perspective view of the saddle which is part of the rack and supports the same from the work beam;

Figure 4 is an enlarged broken away horizontal sectional view of the rack sides with the bar being shown in full lines;

Figure 5 is an enlarged vertical sectional view showing the bars in vertical sectional lines and the parts associated therewith;

Figure 6 is a front elevation of the structure shown in Figure 5;

Figure 7 is a perspective view taken from one side, with parts shown in section of various elements of the clamp;

Figure 8 is a perspective view, taken from the opposite side of the structure shown in Figure 7; and

Figure 9 is a perspective view of the adjustable stud.

Problems having arisen in supporting heavy plates during the electroplating operation of the same. These problems include the easy attachment to and removal from the rack of the articles to be plated, hereinafter termed plates; and the provision of a clamp on the plating rack which will make a good electrical contact with the plate; and the provision of a plating rack which will be rugged enough to withstand the strains imposed upon the same during the plating operation and while the plate is being attached or removed from the rack, without injury to

2

the rack. The present invention overcomes these difficulties without making it necessary to provide a large number of parts to accomplish these results.

Referring to the drawings, the plating rack as a whole is indicated by the letter A. The rack is supported upon the work beam 10 which latter rests upon suitable supports, one of which is indicated at 12 in Figure 2.

The rack is essentially comprised of a pair of spaced parallel vertical sides 14. These sides are mounted upon the lower end of the saddle 16 which is slidably arranged on the work beam 10. The lower end of the saddle supports the rack proper by means of a pair of spacers or washers 18 and the upper end of the sides, washers and the lower end of the saddle are provided with apertures indicated in dotted lines at 20 for the reception of bolts 82.

The parallel sides 14 are held in spaced relation by a series of bars 22. Any number of bars may be provided by drilling or punching holes 24 in the sides 14. After the bars are inserted, the outwardly facing ends of the holes or apertures are closed by welds 26, as shown in Figure 4. The lower bars are arranged closely adjacent to each other as seen in Figures 1 and 2, in order to support the adjustable foot 28. This foot, as shown in Figures 1 and 5, is provided with an upwardly inclined surface 30 and a horizontal surface 32. The back of the foot has a horizontally extending section 34 that extends between a pair of bars 22 and an upwardly turned flange 36. The back of the foot extends vertically from the section 34 to the lower end of the foot in order to provide a vertical resting surface 38 which surface engages a plurality of bars 22, as shown in Figure 5, to thereby form a firm support for the work, such as the plate indicated by the numeral 40.

Extending across adjacent the upper end of the parallel sides and welded thereto at 42 is the fixed block 44. This block has a forwardly projecting face 46, as seen in Figure 1, which latter is provided with an aperture 48, as seen in Figure 8. The lower end of this aperture is provided with threads 50 for engagement by the threads 52 of the stud 54.

The upper end of the stud is provided with a cylindrical portion 54 which engages the bore of the aperture 48. Preferably, the upper end of the aperture is closed by a weld 56, as shown in Figures 2 and 8. Other suitable closure means may be substituted for the weld shown to thereby protect the threads from clogging.

Substantially medially of the stud is an octagonal, or multisided, nut 58 and below this nut are oppositely pitched threads 60. These latter threads, as shown in the several figures, engage the threads 62 of the adjustable block 64.

The lower end of the block 6 is provided with a nose 66 for engagement over the end of the work, and a flat portion 68 for direct engagement with the work. The upper portion of the adjustable block is provided with a horizontally extending flange portion 70 that extends between the parallel sides 14. A removable stop comprises a pin 72 that extends through a pair of the holes 24, in order to prevent downward movement of the block 64 to such an extent that said block will become disengaged from the threads 60 of the stud. It will be appreciated that the threads of the fixed and movable blocks are oppositely turned threads and that these threads are engaged by the oppositely turned threads 52 and 60 of the stud 54 so that the turning of said stud by the engagement of the nut 58 thereof with a suitable tool will cause movements in an up and down direction of the movable block so as to move said block toward or away from the fixed block 44.

In order to properly support a work piece, such as a

plate, for the plating operation, the saddle 16 may be adjusted to proper position along the work beam 10. The movable block is then caused to move upwardly by rotation of the nut 58 in the proper direction. The lengthwise dimension of the plate is then ascertained and the adjustable foot is moved to the position so as to support the plate, as shown in Figure 1, but to leave sufficient clearance for the upper end of the plate to move to the position shown in Figure 1. The nut 58 is then rotated to cause the block 64 to move downwardly so that the flat portion 68 thereof will firmly engage the work piece. By tightening the nut, the work piece will form a rigid connection between the adjustable foot 28 and the adjustable block 64. This contact provides an electrical connection between the work and the plating rack which is unvariable.

As will be noted by reference to the above description and drawings, the instant plating rack may be readily adjustable for different sized work pieces within a minimum amount of time, because very little time is required to adjust the foot 28 and to subsequently tighten the adjustable block 64 to form a firm gripping contact with both ends of the plate.

The above description and drawings disclose a single embodiment of the invention, and specific language has been employed in describing the several figures. It will, nevertheless, be understood that no limitations of the scope of the invention are thereby contemplated, and that various alterations and modifications may be made such as would occur to one skilled in the art to which the invention relates.

We claim:

1. An electroplating rack comprising a pair of generally vertically arranged substantially parallel sides, supporting means for supporting said sides, bars connecting said sides, an adjustable foot supported by said bars having a flanged section supported between said bars and located adjacent the lower end of said plating rack, a fixed block extending between said sides adjacent the upper end of said rack, an adjustable block having a portion extending between said parallel sides, and means including said portion on said adjustable block supporting said adjustable block from said fixed block, said means having actuating means thereon for adjusting said adjustable block toward and from said fixed block, said adjustable foot and adjustable block each having a confronting work engaging face.

2. An electrically conductive electroplating rack comprising vertical supporting means, means for supporting said vertical supporting means on a horizontally extending member, an adjustable foot, an adjustable block, means for supporting said foot and means for supporting block in position whereby either of them may be adjusted toward or from the other, said foot and block having confronting work engaging faces, said means for supporting said foot and block comprising a plurality of spaced supporting elements, said foot having a surface for simultaneously engaging a plurality of said elements whereby to provide good electrical contact between said foot and said supporting elements, and a section on said foot extending between a pair of adjacent elements having an upturned flange provided with a surface engaging the side of one of said elements opposite from the side engaged by the said first-mentioned foot surface.

3. A plating rack, said plating rack comprising means for supporting the same on a horizontal support, a pair of vertical sides connected to said supporting means, a fixed block extending between said sides and rigidly connected thereto, said block having a threaded aperture, an adjustable block, means adjustably and threadedly connecting said threaded aperture of said fixed block to said adjustable block, said sides having a plurality of fixed spaced parallel bars connected to said sides adjacent the lower end of the same, an adjustable foot engaging said

bars, said adjustable foot and adjustable block having confronting work engaging faces, said adjustable foot having a horizontally extending section extending between a pair of adjacent bars, and a flange extending at a right angle to said section.

4. A plating rack, said plating rack comprising means for supporting the same on a horizontal support, a pair of vertical sides connected to said supporting means, a fixed block extending between said sides and rigidly connected thereto, said block having a threaded aperture, an adjustable block, means adjustably connecting said fixed block to said adjustable block, said means adjustably connecting said blocks comprising a stud having oppositely inclined screw threads, said blocks having oppositely inclined screw threads for engagement by said oppositely inclined screw threads first named, means located between said oppositely inclined screw threads on said stud for rotating the same, said sides having a plurality of fixed spaced parallel bars connected to said sides adjacent the lower end of the same, an adjustable foot having a substantially horizontal section extending between a pair of said bars, said section having a back portion extending vertically for engaging one of said bars, said foot having a downwardly extending portion engaging others of said bars, said foot removably engaging said bars whereby the same may be moved to engage others of said bars, said adjustable foot and adjustable block having confronting work engaging faces.

5. A plating rack, said plating rack comprising means for supporting the same on a horizontal support, a pair of vertical sides connected to said supporting means, a fixed block extending between said sides and rigidly connected thereto, said block having a threaded aperture, an adjustable block, means adjustably connecting said fixed block to said adjustable block, said means adjustably connecting said blocks comprising a stud having oppositely inclined screw threads, said blocks having oppositely inclined screw threads for engagement by said oppositely inclined screw threads first named, means located between said oppositely inclined screw threads on said stud for rotating the same, said sides having a plurality of fixed spaced parallel bars connected to said sides adjacent the lower end of the same, an adjustable foot engaging said bars, said adjustable foot and adjustable block having confronting work engaging faces, said adjustable foot having a horizontally extending section extending between a pair of adjacent bars, and a flange extending at a right angle to said section.

6. A plating rack, said plating rack comprising means for supporting the same on a horizontal support, a pair of vertical sides connected to said supporting means, a fixed block extending between said sides and rigidly connected thereto, said block having a threaded aperture, an adjustable block, means adjustably connecting said fixed block to said adjustable block, said means adjustably connecting said blocks comprising a stud having oppositely inclined screw threads, said blocks having oppositely inclined screw threads for engagement by said oppositely inclined screw threads first named, means located between said oppositely inclined screw threads on said stud for rotating the same, said last named means comprising a nut, said sides having a plurality of fixed spaced parallel bars connected to said sides adjacent the lower end of the same, an adjustable foot having a substantially horizontal section extending between a pair of said bars, said section having a back portion extending vertically for engaging one of said bars, said foot having a downwardly extending portion engaging others of said bars, said foot removably engaging said bars whereby the same may be moved to engage others of said bars, said adjustable foot and adjustable block having confronting work engaging faces.

7. A plating rack, said plating rack comprising means for supporting the same on a horizontal support, a pair

of vertical sides connected to said supporting means, a fixed block extending between said sides and rigidly connected thereto, said block having a threaded aperture, an adjustable block, means adjustably connecting said fixed block to said adjustable block, said means adjustably connecting said blocks comprising a stud having oppositely inclined screw threads, said blocks having oppositely inclined screw threads for engagement by said oppositely inclined screw threads first named, means located between said oppositely inclined screw threads on said stud for rotating the same, said last named means comprising a nut, said sides having a plurality of fixed spaced parallel bars connected to said sides adjacent the lower end of the same, an adjustable foot engaging said bars, said adjustable foot and adjustable block having confronting work engaging faces, said adjustable foot having a horizontally extending section extending between a pair of adjacent bars, and a flange extending at a right angle to said section.

8. An electroplating rack comprising a pair of generally vertically arranged substantially parallel sides, supporting means for supporting said sides, bars connecting said sides, an adjustable foot supported by said bars having a flanged section supported between said bars and located adjacent the lower end of said plating rack, a supporting member fixed to said rack adjacent the upper end thereof, an adjustable block having a portion extending between said parallel sides, and means including said portion on said adjustable block supporting said

adjustable block from said fixed member, said means having actuating means thereon for adjusting said adjustable block toward and from said fixed member, said adjustable foot and adjustable block each having a confronting work engaging face.

9. An electrically conductive electroplating rack comprising vertical supporting means, means for supporting said vertical supporting means on a horizontally extending member, an adjustable foot, an adjustable block, means for supporting said foot and means for supporting said block in position whereby either of them may be adjusted toward or from the other, said foot and block having confronting work engaging faces, said means for supporting said foot and block comprising a plurality of spaced supporting elements, said foot having a surface for simultaneously engaging a plurality of said elements whereby to provide good electrical contact between said foot and said supporting elements, and a section on said foot extending between a pair of adjacent elements having 15 a flange provided with a surface engaging the side of one of said elements opposite from the side engaged by the said first-mentioned foot surface.
